DESIGN FOR A PURSE FRAME

Robert F. Roberts, New York, N. Y.

Application November 14, 1942, Serial No. 108,765

Term of patent 14 years

(Cl. D87—2)

To all whom it may concern:

Be it known that I, Robert F. Roberts, a citizen of the United States of America, residing in the Borough of Queens, city of New York, county of Queens, and State of New York, have invented a new, original, and ornamental Design for a Purse Frame, of which the following is a specification, reference being had to the accompanying drawing, forming a part thereof.

I claim:

The ornamental design for a purse frame, as shown.

ROBERT F. ROBERTS.
